[57] CLAIM

The ornamental design for a pet location sign, as shown and described.

DESCRIPTION

FIG. 1 is a front elevational view of the pet location sign of the present invention;

FIG. 2 is a back elevational view of the pet location sign of FIG. 1;

FIG. 3 is a left side elevational view of the pet location sign of FIG. 1;

FIG. 4 is a right side elevational view of the pet location sign of FIG. 1;

FIG. 5 is a top plan view of the pet location sign of FIG. 1; and,

FIG. 6 is a bottom plan view of the pet location sign of FIG. 1.

The broken lines showing of lettering in FIGS. 1 and 2 are for illustrative purposes only and form no part of the claimed design.
